Application November 20, 1930, Serial No. 496,955

5 Claims. (Cl. 153—21)

The present invention relates broadly to the art of metal working, and more particularly to a press adapted for the punching, bending, shaping or the like of pieces of metal. Although the utility 5 of the invention is not limited to the particular function which it performs, it will, for purposes of a clearer understanding, be hereinafter illustrated and referred to as a bending press.

As the size of presses has gradually increased, 10 the weight has been correspondingly increased, until large presses have reached such tremendous sizes and weights as to be extremely expensive, cumbersome and difficult of installation. One of the principal factors contributing to the increased 15 weight has been the fact that it has heretofore been considered essential to construct the press housing of castings, and as the loads to which the castings have been subjected have increased, the area and general mass of the castings has been 20 likewise increased.

It is one of the objects of the present invention to provide a press constructed almost entirely of structural shapes and members as distinguished from castings, whereby the weight and cost of the 25 press as well as its size are all appreciably decreased. The installation and operation of the press is thus facilitated and the room required for a press of given capacity materially reduced. Not only is such reduction in size desirable from 30 the standpoint of the mill in which the press is located, but it is desirable from the standpoint of press capacity itself. This is true for the reason that with structural shapes the different frame parts of the press are more compact, thereby facilitating access to the press not only for 35 repair purposes but for the operation thereof.

With castings as heretofore utilized, there has also been existent the problem of proper mounting of the cylinders utilized for operating the 40 press, the cylinders usually of necessity being supported or carried outside of the main body of the casting. In accordance with the present invention this difficulty is obviated for the reason that it is possible to so assemble the structural 45 members as to provide room for certain of the cylinders within the bodily limits of the housing or frame itself. This constitutes a distinct advantage, as will be readily apparent, not only from the standpoint of compactness, but from the 50 standpoint of protection afforded to the working parts of the mechanism.

It not infrequently happens that it is desired to 55 operate upon material, such as sheets, plates, strips or the like having dimensions such that the ordinary press cannot perform the operations required due to the fact that the material cannot be bodily positioned within the press itself. The size of the cast housings heretofore utilized has 60 precluded the provision of end windows or openings of sufficient sizes to permit the passage

therethrough of work. In accordance with the present invention the end frames, being constructed of structural members, may be readily disposed so as to provide windows or openings therethrough through which work may be inserted 65 or removed at the pleasure of the operator, thereby making it possible by an endwise movement of the work to utilize the press for performing bending, shaping or other operations on metal bodies of materially greater dimensions in one 70 direction than the maximum distance between the end frames of the press.

Another object of the invention is to provide a press having improved operating connections not only possessing desirable features from the 75 standpoint of press operation, but also from the standpoint of control and adjustment of the press.

It has also been found that presses as ordinarily constructed are open to the objection that a press of given capacity cannot be economically utilized 80 for the performance of relatively minor operations inasmuch as the mass to be moved and consequently the power expenditure is out of proportion to the results accomplished. The present invention provides a construction possessing desirable attributes in this respect, since the number of operating means utilized, and consequently the power developed, may be varied at the pleasure of the operator in accordance with the work being performed. In this manner there is provided 85 what may be termed a more or less universal press, the characteristic operation of which may always be kept more or less in step with the operations being performed.

In the accompanying drawings we have shown 90 for purposes of illustration only, a preferred embodiment of the present invention. In the drawings:

Figure 1 is a side elevational view partly broken away, of a press constructed in accordance with 100 the present invention;

Figure 2 is an end elevational view, partly broken away and on an enlarged scale, of the press illustrated in Figure 1;

Figure 3 is a top plan view of the press of Figures 1 and 2;

Figure 4 is a detail sectional view, on an enlarged scale and partly broken away, along the line IV—IV of Figure 1, the operating cylinders 110 being removed;

Figure 5 is a detail sectional view, similar to Figure 4, along the line V—V of Figure 1;

Figure 6 is a detail sectional view on the line VI—VI of Figure 2;

Figure 7 is a vertical sectional view, partly broken away and partly in elevation, along the line VII—VII of Figure 1;

Figure 8 is a detail sectional view, partly broken away and partly in elevation, along the line 120

VIII—VIII of Figure 2, looking in the direction of the arrows.

Figure 9 is a view similar to Figure 2, but partly broken away and illustrating diagrammatically 5 the operating characteristics for the press; and

Figure 10 is a partial side elevational view of the structure illustrated in Figure 9.

Referring more particularly to the drawings, 10 there is illustrated a press comprising end frames 2 connected at their upper portions by a top girder 3 and at their lower portions by a bottom girder 4.

Each of the end frames comprises a pair of corner posts 5 all of which are of generally similar construction, with the exception that two of such 15 corner posts are right hand, and two left-hand. At their bottom portions each pair of corner posts is connected by a transversely extending plate or cross-beam 6 in substantially the same horizontal plane as the bottom girder 4 and to which the 20 ends of the bottom girder 4 are secured in any desired manner.

Similarly, each pair of posts at their upper portion is connected by a transversely extending plate 25 or cross-beam 7 in substantially the same horizontal plane as the top girder 3 to which the ends of the upper girder 3 are connected. Said top and bottom girders together with their cross-beams at the ends, each form a supporting element of substantially H shape in which the 30 girders are arranged to support the upper and lower dies and the actuating mechanism for one of the dies. The upper girder 3, illustrated in detail in Figures 4 and 5 comprises spaced plates 8 and 9 built up to form a girder of box section. 35 These plates are secured to the transverse plate 7 by means of corner angles 10 effective not only for tying the parts together, but for stiffening the same. Overlying the plates 8 and 9 and further assisting in completing and strengthening the top 40 girder, are plates 11 of different lengths and serving to form a truss as will be more apparent from Figures 1 and 3 of the drawings. The top plates 11 are tied to the box girder plates by flange angles 12. These plates are provided with registering 45 openings 14 at predetermined spaced intervals facilitating access to pull back cylinders, as hereinafter more fully described.

Carried by the bottoms of the box girder plates 8 and 9 are bottom plates 15 similarly secured to 50 the box girder plates by flange angles 16. Extending vertically of the box girder plates and serving to stiffen the same are web angles 17 of such length as to have a driving fit between the flange angles 12 and 16.

Secured to the plates 15 and directly underlying 55 the upper box girder 3 and overlying the bottom girder 4, are hydraulic cylinders 18, each cylinder being located substantially below an opening 19 in the bottom plates and in turn registering with 60 the openings 14 before referred to. Positioned within each of the cylinders is a piston 20 operatively secured in any desired manner to the upper flange of an H beam 21, whereby movement of the pistons in one direction will be effective for 65 lowering the H beam, and movement in the opposite direction effective for raising such H beam.

Secured to the under side of the H beam is a 70 male die 22 of a shape depending upon the work which the press is to do, the die herein shown as having a relatively sharp bending edge 23. With the H beam in lower position, the bending die 22, indicated in dotted lines in Figure 7 is effective for bending material M supported by a female die 24 carried by the bottom girder 4. The female die is herein illustrated as comprising

ing a pair of standard rails mounted in normal position and secured in the desired spaced relationship by tie bolts 25 around which are spacer sleeves 26, the rails in turn being bolted in position on the bottom girder by a clamping plate 27 located therebetween and cooperating with the base flanges of the rails.

It will be apparent to those skilled in the art 80 that a die constructed of rails as herein described not only provides an extremely inexpensive structure, but one which may be readily adjusted for causing bending at different angles. Thus by merely removing the bolts 25 and the spacer sleeves 26, and substituting new bolts and sleeves, any desired adjustment of the rails themselves 85 may be obtained.

The pistons 20 before described are effective for 90 accomplishing the downward movement of the H beam 21 and producing the working stroke of the press. For effecting a return movement of the parts, there is provided the pull back cylinder 28 95 cooperating with each of the hydraulic cylinders 18 and directly secured thereto in superimposed relationship. Mounted in each of the pull back cylinders is a piston 29, the upper end of which 100 cooperates with a cross head 30 from which extend tie rods 31. These tie rods are herein illustrated as extending through the openings 19, through openings 32 in the base flanges 33 of the hydraulic cylinders and through suitable aligned openings 105 in the piston heads 34 and the upper flange of the H beam 21, the upper and lower ends of the rods 31 being secured respectively to the yokes 30 and the H beam 21. Due to this construction, when 110 fluid is admitted to the lower ends of the pull back cylinders, the pistons therein will be raised to the position illustrated in Figure 8, and the bending die drawn from its dotted line position of Figure 7 to its full line position ready for a succeeding 115 bending operation.

It is to be noted that we have herein illustrated the H beam, which may be considered as constituting the platen or plunger of the press, as adapted to be moved by the combined action of 120 five hydraulic cylinders 18 suitably spaced lengthwise thereof, and as movable to upper position by an equal number of pull back cylinders. For 125 obvious reasons it is desirable to synchronize the movement of the hydraulic pistons in the various cylinders, and to this end I provide a shaft 35 extending lengthwise of the platen and mounted in suitable bearings 36 carried thereby. At each 130 end, the shaft 35 is provided with a pinion 37 adapted to mesh with a rack 38 secured to a bracket 39 carried by a suitable brace 40 extending transversely between the pairs of corner posts 5. By reason of this construction, the opposite 135 ends of the platen are caused to move substantially equal amounts, any differences being such as permitted only by torsion in the shaft 35. By making the shaft of proper dimensions, however, such torsion may be substantially eliminated.

Cooperating with and opposed to the brackets 39 are similar brackets 41 having bearing plates 42 adapted to cooperate with guide plates 43 on 140 the platen and prevent sidewise movement thereof to such an extent as to permit disengagement between the pinions 37 and the racks 38, and serving further to positively guide the platen in its reciprocal movements.

By reference more particularly to Figure 2 of the drawings, it will be noted that the space between the brace 40 and the bottom girder 4 is substantially unobstructed except for the brackets 145 39 and 41. Since, however, these brackets pro-

ject downwardly a distance less than the projection of the bending die 22, they do not interfere with the movement of material endwise between adjacent corner posts 5. Since these corner posts 5 must be of sufficient strength to prevent yielding movement between the upper and lower girders 3 and 4, respectively, and such as to prevent any deflection during the operation of the press, they are preferably of built up construction. To this 10 end we preferably provide laterally extending wings 44 preferably integral with the transversely extending plates 6 and 7 before referred to, the entire plate being punched out to provide the end windows or unobstructed spaces before described.

15 For stiffening the end plates, they may have secured thereto tapered plates 45 bolted or riveted in position through the medium of corner angles 46 on their outer sides, these corner angles extending the full height of the end plates, and by 20 inner angles 47 adjacent the transverse plates 7 and similar angles 48 adjacent the transverse plates 6. Disposed on the opposite sides of the end plates from the tapered plates 45 are angles 49 similar to the angles 46 and extending the full 25 height of the end plates. These angles are so mounted that their inwardly projecting flanges lie in the plane of the tapered plates 45 as will be clearly apparent more particularly from Figure 6 of the drawings, whereby they define the sides 30 of the end windows. It will thus be apparent that there are provided corner posts which are braced in each of four directions, thus providing the necessary strength and stiffness without resort to cumbersome castings as heretofore utilized.

35 The smaller space required for such structural posts makes possible the end windows through which material may be fed to or removed from the press.

In Figures 9 and 10 of the drawings there are 40 illustrated connections by means of which the desired operation of the press may be easily obtained. In Figure 9 there is indicated a tank 50 constituting a suitable source of fluid supply having a pipe 51 leading to the inlet of a pump 52. The outlet 53 of the pump is branched, the branch 45 54 leading to a release valve 55 the outlet of which has a connection 56 to the inlet of the pump and effective when the release valve is open for by-passing the pump and thereby preventing the 50 generation of pump pressure in the system. The other branch 57 of the outlet 53 leads to a check valve 58 of such construction as to freely permit the passage of fluid therethrough in the direction indicated by the arrow 59, but preventing 55 the passage of fluid in the opposite direction.

The outlet 60 of the check valve communicates with a T 61 having a connection 63 leading to the lower ends of the pull back cylinders 28. The T also has a connection 64 leading to a two-way control valve 65. With the valve in one position it will permit fluid to flow from the pull back cylinders by way of connections 63, T 61 and connection 64 to pipes 66 leading to the hydraulic cylinders 18, thus permitting the pull back cylinders to discharge into the hydraulic cylinders, while with the valve in its other position, it will permit fluid to flow from the hydraulic cylinders by way of the pipe 66 to a return line 67 discharging into the tank or reservoir 50.

60 The release valve 55 is suitably carried by the frame of the press in such manner that the valve stem 68 thereof may cooperate with a pivoted lever 69 carrying the counterweight 70. Secured to the lever 69 is a cable 71 passing upwardly over a pulley 72 and thence downwardly over a second pulley 73 on the box girder 3 to a weight 74, heavier than the counterweight 70 and effective for overcoming the same. As the press reaches its upper position, the upper surface of the H beam or platen 21 will engage the weight 74 and lift the same, thus releasing tension on the cable 71 and permitting the counterweight 70 to move downwardly and open the release valve 55, thus bypassing the pump 52 and releasing pressure from the system. At this time, however, descent of the platen will be prevented by the pull back cylinders, the fluid being trapped in these cylinders through the medium of the check valve 58. This condition will continue until such time as it is desired to set the press into operation. At such time, the control valve 65 will be operated to connect the pull back cylinders to the hydraulic cylinders so that the pull back cylinders will discharge into the hydraulic cylinders permitting the platen to descend by gravity. After this movement has been initiated, the platen 21 will withdraw from supporting relationship with the weight 74 which will in turn be effective for overcoming the counterweight 70 and closing the release valve 55 whereby the pump by-pass is closed and the pump pressure directed into the hydraulic cylinders 18 for forcing the platen downwardly.

65 At such time as the down stroke has progressed to the desired point, an adjustable stop screw 75 carried by the platen 21 will engage a bell crank 76 and swing the same about its pivotal mounting 77 to release the tail 78 thereof from holding engagement with a lever 79 having a pivotal mounting 80. Connected to the lever is a cable 81 to one end of which is secured a weight 82, the opposite end passing upwardly over a pulley 83 and around a pulley 84 and then attached to the cable 71. When the tail 78 moves out of engagement with the lever 79, the weight 82 is effective for overcoming the weight 74, lifting the same and thus enabling the counterweight 70 to open the release valve 55. In this manner the down stroke of the platen is automatically stopped at a predetermined time depending upon the adjustment of the stop screw 75. Suitable adjustment of this screw enables the stroke of the press to be lengthened or shortened at the will of the operator as will be readily apparent.

70 In case of necessity, the operator may check the down stroke at any desired interval by means of the trip handle 85. Outward movement of this handle against the spring 86 will be effective for swinging the bell crank 76 and releasing the lever 79.

75 When it is desired to lift the male die, the operator bears down on the handle portion 87 of the lever 79, thereby lifting the weight 82, closing the release valve 55 and reestablishing fluid pressure in the system, the control valve 65 at this time having been turned to such position as to permit the hydraulic cylinders to discharge therethrough into the return connection 67, whereby the pressure of the pump will be effective only in the pull back cylinders. It will be apparent that the downward movement of the handle portion 87 of the lever 79 causes it to move past the bell crank lever which immediately snaps into holding engagement therewith under the influence of the spring 86.

80 We have herein illustrated all of the hydraulic cylinders as cooperating with a single platen. From Figure 2 of the drawings, however, it will be apparent that the connection 66 from the control valve has an independent connection 66' 150

to each of the hydraulic cylinders, each of which connections is controlled by an individual valve 88. Thus if desired, any number of the hydraulic cylinders may be quickly cut out of operation to 5 effect a corresponding change in the capacity of the press. The invention also lends itself to a division of the platen 21 into a plurality of parts each under the control of an individual hydraulic cylinder or under the control of any number of 10 hydraulic cylinders, thus giving a number of individual presses each of the desired capacity for the performance of a particular operation. In such case a suitable change in the number of control valves may be made so as to provide for the 15 desired automatic control of any cylinder or group of cylinders.

Advantages of the invention arise from the provision of a structural frame and particularly from the provision of such a frame having end 20 windows and from the provision of a box girder within which the pull back cylinders may be positioned.

Further advantages arise from the provision of a press including a plurality of hydraulic cylinders or other operating means of such construction and so mounted that any number may be utilized at will independently of the others, or simultaneously therewith for the operation either of a single platen or a plurality of different 30 platens.

Still other advantages obtainable from a female die of the construction referred to, and from the automatic control features whereby automatic shut-off on the down stroke of the press is obtained have hereinbefore been referred to.

While we have herein illustrated and described a preferred embodiment of our invention, it will be understood that changes in the construction and operation of the parts may be made without departing either from the spirit of the invention or the scope of our broader claims.

We claim:

1. A bending press having a frame comprising upper and lower supporting elements of substantially H shape built up of structural shapes, formed of two cross-beams and a girder connected to the intermediate portions of the cross-beams, posts built up of structural shapes connected to the ends of cross-beams of the supporting elements, a die member supported on the girder of each element, and means on one of the elements for actuating the die member associated therewith.

2. A bending press having four spaced apart posts built up of structural shapes, a lower supporting element of substantially H shape built up of structural shapes, formed of two cross-beams and a girder connected to the intermediate portions of the cross-beams, each end of each cross-beam being connected to one of the posts, an upper supporting element of substantially H shape built up of structural shapes, formed of two cross-beams and a box-girder connected to the intermediate portions of the cross-beams of said upper supporting element, each end of each cross-beam of the upper supporting element being connected to one of the posts, a stationary die member secured to the girder of the lower supporting element, a movable die member above the fixed die member, and means on the box girder for supporting and moving the movable die member relative to the fixed die member.

3. A bending press having four spaced apart

posts built up of structural shapes, a lower supporting element of substantially H shape built up of structural shapes, formed of two cross-beams and a girder connected to the intermediate portions of the cross-beams, each end of each cross-beam being connected to one of the posts, an upper supporting element of substantially H shape built up of structural shapes, formed of two cross-beams and a box-girder connected to the intermediate portions of the cross-beams of said upper supporting elements, each end of each cross-beam of the upper supporting element being connected to one of the posts, a stationary die member secured to the girder of the lower supporting element, a movable die member above the fixed die member, a hydraulic cylinder connected to the bottom of the box girder, a piston in said cylinder connected to the movable die member, a pull back cylinder above the hydraulic cylinder within the box girder, a pull back piston within the pull back cylinder extending upwardly within the box girder, a cross head on the outer end of the pull back piston within the girder, and pull back rods connected to the cross head and the movable die member.

4. A bending press having four spaced apart posts built up of structural shapes, a lower supporting element of substantially H shape built up of structural shapes, formed of two cross-beams and a girder connected to the intermediate portions of the cross-beams, each end of each cross-beam being connected to one of the posts, an upper supporting element of substantially H shape built up of structural shapes, formed of two cross-beams and a box-girder connected to the intermediate portions of the cross-beams of said upper supporting elements, each end of each cross-beam of the upper supporting element being connected to one of the posts, a stationary die member secured to the girder of the lower supporting element, a movable die member above the fixed die member, a plurality of hydraulic cylinders connected to the bottom of the box girder, a piston in each of said cylinders connected to the movable die member, a pull back cylinder above each of the hydraulic cylinders within the box girder, a pull back piston within each of the pull back cylinders extending upwardly within the box girder, a cross head on the outer end of each pull back piston within the girder, and pull back rods connected to each of the cross heads and the movable die member.

5. In a press, a stationary die, a movable die, a piston and cylinder for operating the movable die, a pull back piston and cylinder for retracting the die, a fluid pressure supply for continuously supplying fluid, fluid connections between said supply and the two cylinders, valve means in said fluid connections for connecting either cylinder with the fluid pressure supply and exhaust the fluid from the other cylinder, a release valve in said fluid connections arranged to by-pass the fluid around the cylinders when opened, and means associated with the movable die arranged to open the release valve when the die has moved a predetermined distance in either direction, to stop the movement of the die, regardless of the pressure in either cylinder, without shifting the first valve means and without stopping the flow from the fluid pressure supply.

JOHN R. BRADLEY.
LINDSAY R. CHRISTIE.
